US00D707690S

(12) **United States Design Patent**
Billington

(10) **Patent No.:** **US D707,690 S**
(45) **Date of Patent:** **** Jun. 24, 2014**

(54) **USB MEMORY DEVICE**

(71) Applicant: **Charles Billington**, London (GB)

(72) Inventor: **Charles Billington**, London (GB)

(73) Assignee: **Groundhog S.A.**, Luxembourg (LU)

(**) Term: **14 Years**

(21) Appl. No.: **29/456,736**

(22) Filed: **Jun. 3, 2013**

(30) **Foreign Application Priority Data**

Jan. 10, 2013 (EM) 002164392-0002

(51) **LOC (10) Cl.** **14-02**

(52) **U.S. Cl.**

USPC **D14/480.7**

(58) **Field of Classification Search**

CPC H05K 5/0278; G06K 19/07732

USPC D14/411, 433, 435.1, 436, 480.1-480.7,
D14/484.1, 137, 155, 203.1-203.8, 240,
D14/242; D13/133, 154

See application file for complete search history.
